E. D. CAMPBELL

ROLLER IRON

Filed Sept. 24, 1924

UNITED STATES PATENT OFFICE.

ELLIOTT D. CAMPBELL, OF SAN FRANCISCO, CALIFORNIA.

ROLLER IRON.

Application filed September 24, 1924. Serial No. 739,635.

To all whom it may concern:

Be it known that I, ELLIOTT D. CAMPBELL, a citizen of the United States, and a resident of San Francisco, in the county of San Francisco and State of California, have invented a new and useful Roller Iron, of which the following is a specification.

The present invention relates to improvements in roller irons and has for its particular object to provide means whereby ironing, particularly the ironing of flat pieces, can be accomplished at a high rate of speed. It is proposed for this purpose to provide an iron that is substantially co-extensive in length with the width of an ironing board and provided with means preventing lateral shifting of the iron as the same is advanced over the board so that the entire width of a piece of cloth lying on the ironing board is pressed by a single stroke. It is further proposed to provide in combination with this feature means yieldingly spacing the iron from the board so that there is no danger of burning the cloth to be pressed in the absence of the person operating the iron. It is further proposed to utilize an electrically heated iron and more particularly electrically heated rollers enclosed in a casing and projecting from the bottom thereof. Further objects and advantages of my device will appear as the specification proceeds.

The preferred form of my invention is illustrated in the accompanying drawing, in which—

Figure 1 shows in perspective view my combination iron and ironing board;

Figure 2 an enlarged sectional view taken along line II—II of Figure 1;

Figure 3 an enlarged detail view, partly in plan and partly in horizontal section, of my iron, and

Figure 4 a detail view of my heating element and Figure 5 a cross section through a clamp used in my device.

While I have shown only the preferred form of the invention, it should be understood that various changes or modifications may be made within the scope of the claims hereto attached without departing from the spirit of the invention.

My ironing board 1, the central portion of which is broken away in Figure 1, and which is flat and rectangular in form, is preferably supported by angle irons 2, one vertical flange 3 of which lies against each

side of the ironing board while the second flange 4 extends laterally from the lower edge thereof, the latter flange being preferably curved upwardly at one end as shown at 6 to limit the travel of the element riding thereon which will be mentioned hereinafter. A clamp 7 consisting of two yieldingly connected jaws 7^a and 7^b is mounted to slide longitudinally on the board 1 at one end thereof. These jaws are adapted to engage with one end of the cloth to be pressed so that when the iron is engaged with the opposite end of the cloth, the cloth will be taken up so as to remove the wrinkles therefrom preparatory to moving the iron from one end of the board to the other. This clamp is connected to the board by means of springs 7^c which tend to draw the clamp toward the end of the board and thereby places the cloth to be pressed under slight tension when the other end or an intermediate portion of the cloth is weighted down by the iron. Slots 8 are provided on each side of the ironing board between the angle iron 3 and the body of the board to allow a cloth 9 to encircle the ironing board and to be fastened by means of springs 11.

My iron comprises a rectangular casing 12 coextensive in length with the width of the ironing board so that when the casing is placed transversely on the board, the end faces of the casing are flush with the sides of the board, and when the iron is tipped back to rest on the flat face 12 of the casing the ironing rollers will be elevated clear of the board. Lugs 13 extend from the ends of the casing and guide vertical pins 14 which latter are provided with rollers 16 engaging with the flanges 3 of the angle irons to ride along the edges of the board and to prevent the iron from shifting laterally. The pins 14 terminate at the bottom ends in ball shaped cups 17 adapted to receive the balls 18 which latter ride on the horizontal flanges 4.

Spring 19 are introduced between collars 21 on the pins 14 and the lower lugs 13 tending to normally force the casing upwardly into an inoperative position so that it requires pressure on the part of the operator to force the iron into contact with the material to be pressed. The casing has a U-shaped heating element 21 supported in its end walls so that the legs of the element extend throughout the length of the box and rollers 22 are made revolvable on the heating element and are disposed to project beyond

the open end of the casing as shown at 23. The heating element 21 may be made of conventional form and I prefer to use electricity for heating the element by allowing a current to flow through the windings 24 surrounding the heating element. The handle 26 is placed on top of the casing so as to allow of the easy manipulation of the same.

The manner of using the iron will be readily understood from the foregoing description. The sheet of material to be pressed is placed on the board and one end of the same is engaged with the clamp 7 for the purpose stated. The iron is then placed transversely on the board near the opposite end thereof so that its rollers engage with the sides of the board and the balls 18 ride on the horizontal flanges 4. The springs 19 normally hold the iron out of contact with the material to be worked on. To effect operative contact, the operator depresses the casing and advances the same over the sheet of material so that the full width of the same is pressed at one time.

25 I claim:

1. In combination, an ironing board having flanges extending from the lower lateral edges thereof, an iron substantially coextensive in length with the width of the board 30 having vertical pins slidably associated with the ends thereof adapted to ride on the flange and yielding means associated with the pins tending to lift the iron off the board.

2. In combination, an ironing board having flanges extending from the lower lateral edges thereof, an iron substantially coextensive in length with the width of the board having vertical pins slidably associated with the ends thereof adapted to ride on the flange 40 and yielding means associated with the pins tending to lift the iron off the board, the pins having rollers thereon engaging with the sides of the board for preventing the lateral shifting of the iron.

45 3. A portable iron of the character described comprising an elongated casing of

rectangular cross-section and of a length corresponding to the width of an ironing board so as to control the entire transverse area thereof, heating rollers arranged in parallel relation therein so as to project with their peripheries through the open bottom of the casing and a handle on top of the casing allowing the same to be manually operated, the casing presenting a flat side extending transversely of the ironing board allowing the casing to be tilted and to come to rest on said side with the rollers elevated from the board.

4. A portable iron of the character described comprising an elongated casing of uniform cross-section and of a length corresponding to the width of an ironing board so as to control the entire transverse area thereof, heating rollers arranged in parallel relation therein so as to project with their peripheries through the open bottom of the casing and a handle on top of the casing allowing the same to be manually operated, the casing having guiding elements depending from at least one end thereof with rollers thereon made for engagement with the vertical edge of the ironing board to prevent lateral shifting of the iron, but preserving its freedom for vertical movement.

5. Means for ironing a plain sheet of cloth or the like comprising a rectangular ironing board adapted to have the cloth placed thereon, slideable clamping means adapted to clamp one end of the sheet having yielding means for securing the same to one end of the ironing board associated therewith and an elongated iron substantially coextensive in length with the width of the ironing board having heating rollers projecting through the open bottom thereof and being adapted through its weight to cooperate with the clamping means in maintaining the cloth in a stretched condition while being guided over the same.

ELLIOTT D. CAMPBELL.
